UNITED STATES PATENT OFFICE.

FREDERICK W. MILLER, OF LOS ANGELES, CALIFORNIA.

ELECTRIC-ARC LAMP.

1,329,132.

Specification of Letters Patent. Patented Jan. 27, 1920.

Application filed March 8, 1919. Serial No. 281,476.

To all whom it may concern:

Be it known that I, FREDERICK W. MILLER, a citizen of the United States, residing at Los Angeles, in the county of Los Angeles and State of California, have invented new and useful Improvements in Electric-Arc Lamps, of which the following is a specification.

This invention contemplates certain new and useful improvements in the feeding mechanism of arc lamps, and is especially adaptable for use with three carbons forming in effect a single arc.

The objects of this invention are first, to provide feeding mechanism for carbons which will simultaneously advance carbons at the same speed, thereby maintaining the arc at a selected point; second, to provide a mechanism which will feed carbons with a progressive uninterrupted motion; and third, to provide details of structure, whereby a simple, durable, compact structure, easy to manipulate, is secured.

These objects will be more fully understood, as will also other objects and corresponding accomplishments of my invention from the following detailed description of a preferred embodiment of the invention. For the purpose of this description reference is had to the accompanying drawing, in which:

Figure 1 is a side elevation of the feed mechanism mounted in a flood lamp casing, the latter being shown in dotted lines; Fig. 2 is a front elevation; Fig. 3 is an elevation on an enlarged scale of the feed plate; Fig. 4 is an elevation of the cover plate; and Fig. 5 is a fragmentary section on an enlarged scale taken on the line 5—5 of Fig. 2.

The invention as disclosed herein is embodied in a three phase alternating current arc lamp. Three carbons are brought together at a single point, each carbon being connected to one phase of the system. The result is that a single arc in effect is formed at the meeting point of the carbons, this arc being substantially constant in its light intensity. Single arcs formed by taking current between any two of the three phases will produce a flickering light depending upon the frequency of the alternations. To overcome this, three arcs each on a different phase have been used, so that the phase relation of the flickering will produce in effect a constant intensity of light. My invention

is especially adapted to the use of three carbons and a single arc on a three phase system, although not limited to such use.

Referring more particularly to Fig. 1, A 60 indicates the lamp casing for a flood light, B the condenser and C the arc mechanism. It is usual to have a means of focusing the arc. In the present case this is accomplished by having a hollow lug 6 in the 65 nature of a sleeve attached to the lamp casing, and sliding therein a tube 7 to which the arc mechanism is attached, so that the arc may be advanced or retracted within the lamp casing. A thumb screw 8 serves to 70 fasten or secure the arc in any focused position.

Tube 7 is attached to a feed plate casing 9, and, at the other end is provided with a hand knob 7' for convenience in moving the 75 arc mechanism when focusing. Within the feed plate casing 9 is a feed plate 10 mounted so that it may be rotated. For the purpose of rotating the feed plate a shaft 11 is attached thereto and extends through the 80 tube 7 and knob 7', being provided at one end with a hand knob 12 for convenience in its manipulation. The face of the feed plate is provided with a spiral groove 13. Secured to casing 9 is a cover plate 14, which 85 also serves as a guide for carbon feeder arms 15. As the feeder arms are duplicates of each other, only one will be described. Referring particularly to Fig. 5, feeder arm 90 15 is square in transverse section and provided preferably with a shoe 16 having teeth engaging the spiral groove 13. The cover plate 14 is provided on its inner face with guide grooves 17 disposed 120° apart and so constructed that the feeder arms will 95 slide therein. The cover plate securely holds the feeder arms in position with the teeth in engagement with the groove 13 in the feed plate. Secured to the feeder arm 15 is a holder arm 18, which is insulated 100 therefrom. Any type of carbon holder may be used, but I prefer to provide the ends of the arm with an enlargement of sleeve like form having a semi-cylindrical lip 20 secured thereto and a movable lip 21, which 105 is forced against the carbon by means of a thumb screw 22. The carbons 23 are placed in the holders and clamped between the lips 20 and 21.

The elements of the mechanism are so assembled that the feeder arms 15 are substantially the same distance from the center

of the feed plate. The carbons are adjusted so that the arc will be formed in line with the center of the feed plate. As the carbons burn away knob 12 is grasped and turned, 5 thereby turning feeder plate 10. By rotating the knob in the proper direction the feeder arms will be moved inwardly toward the center of the feeder plate following the groove of the spiral. This advances the carbons toward each other. It will be noted that there is a simultaneous, uninterrupted 10 progressive movement of the carbons.

Although I have disclosed a means for manually adjusting the carbons, yet my invention is not limited to this mode of adjustment. Automatic mechanism may be provided for advancing and retracting the carbons, such construction coming within the scope of my invention. Various 15 mechanical expedients may be resorted to without departing from my invention, which resides particularly in the feeding plate and its coöperating parts.

What I claim is:

- 25 1. The combination in an arc lamp of a plurality of carbon feeder arms, and a rotatable plate having a spiral way with which said arms are engaged whereby rotation of said plate will move said arms to and from each other, so as to uniformly feed the carbons to a common point which determines the position of the arc.
- 30 2. The combination in a three phase arc lamp of three carbon feeder arms, and a rotatable plate having a spiral way with which said arms are engaged, whereby rotation

of said plate will move said arms to and from each other, so as to uniformly feed the carbons to a common point which determines the position of the arc.

3. The combination of a casing, a rotatable plate therein having a spiral way, a plurality of carbon feeder arms having teeth thereon in engagement with said way, and a cover plate for said casing having radial guides one for each of said arms, whereby carbons are uniformly fed to a common point which determines the position of the arc.

4. The combination of a sleeve, a casing having an extension slidably mounted in said sleeve for focusing, a rotatable plate in said casing having a spiral way, a carbon feeder arm having teeth thereon in engagement with said way, and a cover plate for said casing having a radial guide for said arm.

5. The combination of a sleeve, a casing having a tubular extension slidably mounted in said sleeve for focusing, a rotatable plate mounted in said casing having a spiral way, a rod secured to said feeder plate and extending through said tubular extension for rotating said plate, a carbon feeder arm having teeth thereon in engagement with said way, and a cover plate for said casing having a radial guide for said arm.

In witness that I claim the foregoing I have hereunto subscribed my name this 26th day of February, 1919.

FREDERICK W. MILLER.
